BEVERAGE DISPENSER FOR ICED TEA
OR THE LIKE

Channing Wallace Gilson, Los Angeles, Calif., assignor to Columware, Inc., Lynwood, Calif., a corporation of California

Filed Aug. 19, 1968, Ser. No. 13,188

Term of patent 14 years

Int. Cl. D15—12, 99

U.S. Cl. D94—3

FIGURE 1 is a perspective view of a beverage dispenser for iced tea or the like, showing my new design;

I claim:

The ornamental design for a beverage dispenser for iced tea or the like, substantially as shown and described.
